(57) **CLAIM**

The ornamental design for a bottle, as shown and described.

DESCRIPTION

FIG. 1 is a top, front, left-side perspective view showing the new bottle design;

FIG. 2 is a top plan view thereof;

FIG. 3 is a front, elevational view thereof;

FIG. 4 is a right side elevational view thereof;

FIG. 5 is a rear, elevational view thereof;

FIG. 6 is a left side elevational view thereof; and,

FIG. 7 is a bottom plan view thereof.

The broken lines in the drawings are for environmental purposes only and form no part of the claimed design.

The boundary of the claimed design extends to the outermost broken line edge of the unclaimed bird.
